DESIGN FOR A FOOTREST

Ray Smith, Tulsa, Okla.

Application April 6, 1943, Serial No. 109,910

Term of patent 14 years

(Cl. D15—8)

To all whom it may concern:

Be it known that I, Ray Smith, a citizen of the United States, residing at Tulsa, in the county of Tulsa and State of Oklahoma, have invented a new, original, and ornamental Design for a Footrest, of which the following is a specification, reference being had to the accompanying drawing, forming part thereof.

Figure 1 is a rear elevational view of a footrest, showing my new design;

Figure 2 is a side elevational view;

Figure 3 is a front perspective view; and

Figure 4 is a top plan view thereof.

I claim;

The ornamental design for a footrest, as shown.

RAY SMITH.
